UNITED STATES PATENT OFFICE.

EDWARD A. GRAPP, OF MINNEAPOLIS, MINNESOTA.

REGISTER CONSTRUCTION FOR HEATING PLANTS.

Application filed April 1, 1927. Serial No. 180,262.

This invention relates to improvements in moist or hot air heating system equipment, and the primary object is to provide an improved construction of register wherein the 5 same may be tightly fitted against the wall in order to prevent the escape of air and dust upwardly along the wall and thereby prevent the streaking and soiling of the wall by such escaping air and dust. Further and more 10 specific objects will be disclosed in the course of the following specification, reference being had to the accompanying drawing, wherein:

Fig. 1 is a perspective view of my improved register.

Fig. 2 is an enlarged sectional elevation as on the line 2—2 in Fig. 1, and illustrating the association of the wall and air stack which are also shown in section.

Fig. 3 is an enlarged detail perspective view showing one of the upper corners of the register, as seen from within.

Referring to the drawing more particularly and by reference characters, A designates the floor and B the wall of a room, which is heated 25 from the register C which is connected with the hot air pipe or stack D, which projects up through the floor and wall from the heating plant (not shown) in the basement.

The register C is of the sloping shell type, 30 having a gridded face 4 and a marginal flange 5. The register is further provided, about the limits of the grille 4, with a rearwardly projecting inner flange 6, which fits snugly with the end of the air stack D, so that the 35 upcoming warm air can only escape through the grid 4. The register is also provided with the usual shutter or damper 7, the position of which may be manually regulated by a hand lever 8. Secured upon the inner 40 side of and extending along the entire rear edges of the flanges 5, I provide a resilient, rearwardly projecting strip 9 which may be made of felt, leather or any other suitably flexible material. This strip is suitably 45 secured and held in place by a metallic strap 10, which forms a channel with the flange 5, for receiving the strip, and has an offset shoulder or rim 11 by which it may be secured to the flange 5 as by welding, brazing, 50 riveting or the like.

It is a well known fact that the streaking and soiling of walls above registers of this

class is a common and very disagreeable occurrence, and that it is due to the further fact that it is practically impossible to fit 55 the register shell against the wall without leaving crevices through which air may escape upwardly, because most registers are placed directly against the face of the plaster and such plaster faces almost always present an irregular contour. This difficulty has long been recognized and while some attempts have been made to overcome it, those attempts that have come to my attention have been unsuccessful largely due to the fact that 60 the situation is not fully understood. Thus, for instance, it has been assumed that the dirt streaks have resulted from an escape of the heated air which comes up through the flue or stack D, with a result that various attempts have been made to seal or close the joints between the flange 6 and the end of the flue D. This is shown for instance in the 65 Patent No. 1,336,210, to Druliner. But even when the 6—D joint is made perfectly tight 70 it is found that the streaking of the wall continues as before, and for the following reason. I have found that it is not usually the heated air from the furnace, that comes up within the stack D, that is the source of the 75 trouble, but, rather, the air about the stack and within the shell 5, which upon becoming warmed by the stack starts to circulate and escapes through any crevice that it finds, and as it escapes it is replaced by other air which 80 may either creep up under the lower edge of the shell or may follow the outer surface of the stack, from the basement, through the 85 holes which have been cut in the wall and floor to accommodate the stack.

When my improved register is put in place, it is securely fastened, against the wall, and as the strip 9 is flexible it will yield according to the contour of the wall, thus insuring an air tight joint between the wall and the entire 95 register shell. The air within the shell is now confined, and while it may circulate to a limited extent, it cannot escape into the room, and consequently cannot effect the objectionable deposit of dust upon the adjacent 100 wall surface.

It is understood that suitable modifications may be made in the general design and structural details of the invention as herein shown,

provided, however, that said modifications come within the spirit and scope of the appended claim.

Having now therefore fully shown and described my invention, what I claim to be new and desire to protect by Letters Patent is:

A warm air register comprising a shell having a grilled face portion, through which the warm air may pass from a stack, and hav-

ing a marginal flange spaced from the stack, 10 a yieldable element extending about the edge of said flange, and means for securing the element to the inner face of the flange, said means comprising a strap secured to the inner face of the flange and forming a channel 15 therewith for holding the element.

In testimony whereof I affix my signature.
EDWARD A. GRAPP.
